UNITED STATES PATENT OFFICE.

JAMES W. PYLE, OF NEW YORK, N. Y.

AUTOMATIC PUMP-LOCK AND DEAD-LINE KILLER FOR MONOTYPE-MACHINES.

1,116,734.

Specification of Letters Patent.

Patented Nov. 10, 1914.

Application filed April 26, 1910. Serial No. 557,659.

To all whom it may concern:

Be it known that I, JAMES W. PYLE, a citizen of the United States, and a resident of the city of New York, borough of Manhattan, in the county and State of New York, have invented a new and Improved Automatic Pump - Lock and Dead - Line Killer for Monotype-Machines, of which the following is a full, clear and exact description.

This invention relates to certain improvements in that form of monotype casting machine commonly known as the "Lanston", and relates more particularly to the controlling of the pump and the galley trip rod. In the operation of the Lanston machines as now manufactured, it often happens that the keyboard operator makes a mistake in a line and discovers the mistake before completing the line. It is then necessary for him to complete the line with x's or any other character and justify the line. He then begins again and writes the line as he desires to have it. When the perforated strip goes to the casting machine, the end of the strip which was perforated last enters the casting machine first and the good line, as well as the spoiled line, is cast. It is then necessary for the operator of the casting machine to pick out the entire spoiled line and throw away the type. If he does not do this, the galley-proof will show the good line as well as the spoiled line and unless the spoiled line is noticed by the proof-reader, it will eventually appear in the paper.

The object of my invention is to avoid the necessity for completing a line after the key-board operator discovers he has made a mistake and to avoid the necessity for casting the spoiled line. By means of my improvement time is saved at the keyboard and at the casting machine, and the necessity for picking out and throwing away spoiled or dead lines will be avoided. In order to secure this object, I provide means whereby the justification wedge lever which formerly gave the galley trip rod its longer stroke, will give said trip rod its shorter stroke, and whereby the justification wedge lever which gave the galley trip rod its shorter will give it its longer stroke. I also provide means for locking the galley trip rod against return movement after its shorter stroke, and until it is given its longer stroke, so that the pump will remain

locked and no type will be cast while the galley trip rod remains at the end of its shorter stroke.

Reference is to be had to the accompanying drawings, forming a part of this specification, in which similar characters of reference indicate corresponding parts in all the figures and in which I have illustrated a portion of a monotype machine having my improvement applied thereto.

Figure 1 is a vertical section through a portion of a machine and illustrating the galley trip rod and pump trip tube and the mechanism for operating the same; Fig. 2 is a vertical section through a portion of the bed of the machine, showing my retaining pawl applied thereto; Fig. 3 is a transverse section on the line 3—3 of Fig. 2; Fig. 4 is a side elevation similar to a portion of Fig. 1 but showing the galley trip rod at the end of its longer stroke; Fig. 5 is a top plan view of the galley trip rod in its normal position; Fig. 6 is a view similar to Fig. 5, but showing the galley trip rod at the end of its shorter stroke; Fig. 7 is a view similar to Figs. 5 and 6, but showing the galley trip rod at the end of its longer stroke; and Fig. 8 is a portion of a record strip perforated for use with my improved attachment.

One form of monotype casing machine to which my invention may be applied is partly illustrated in Fig. 8 of the patent to Bancroft, No. 674,374, granted May 21, 1901. In this form there is employed a galley trip rod 8D mounted within suitable guides and movable longitudinally. Adjacent one end of this galley trip rod is the trip lever 45F, mounted to swing upon the trip lever fulcrum screw 46F. The end of the trip lever is disposed in the path of the galley trip rod and it carries a plurality of set screws, by means of which the normal position and the time of contact with the galley trip rod may be controlled. The opposite end of the trip lever serves for controlling the line hook, as is well understood by those familiar with this type of machine. The galley trip rod at its opposite end, is rigidly connected to the galley trip rod member 9D, to which is mounted the rock lever 9D¹. This rock lever is pivoted intermediate its ends upon a fulcrum pin 9D² and swings in a horizontal plane. Pivoted above the rock lever 9D¹ are two justification wedge levers 13D and 14D, each having a

depending portion adjacent its corresponding end of said rock lever. Each justification wedge lever is pivotally connected to a 5 justification wedge lever arm rod 15D³, the upper end of which latter is free to swing into or out of engagement with the centering pin lever 16E. Adjacent the pivotal support of the two justification wedge levers is the air pin block 3D, within which are 10 the air pins 1D. Pivotally supported adjacent each air pin is a bell crank 4D, one end of which is in engagement with its corresponding air pin and the other end of which serves to swing its corresponding rod 15D³ into or out of engagement with the centering pin lever. As a justification hole in the record strip passes the air outlet, air is permitted to pass to the corresponding pin 1D and the corresponding rod 15D³ is 15 swung into engagement with the centering pin lever 16E. The upward movement of the latter raises the corresponding justification wedge lever and the depending end of the latter engages with the corresponding 20 end of the rock lever 9D¹ to swing the latter. The rock lever is prevented from swinging on its pivot any great distance as the opposite end strikes the other wedge lever, and the further swinging of the rock lever causes 25 a bodily movement of the rock lever and a corresponding longitudinal movement of the galley trip rod 8D.

Substantially parallel to the galley trip rod 8D is a pump trip tube 49D, slideable 30 within suitable guides. This pump trip tube has a collar 49D¹ thereon, which is normally out of engagement with a pump latch 33H¹, (see dotted lines in Fig. 1) but which may be moved into engagement with the 35 latter to lock the pump against operation when the pump trip tube is moved lengthwise to the required distance. For moving this pump trip tube a lever 48D is pivoted to a portion of the frame of the machine, 40 and has its lower end adjacent the rear end of the pump trip tube. The depending portion of the galley trip rod arm 9D engages with this lever 48D intermediate the ends of the latter, so that as the trip rod 8D is 45 moved lengthwise, the pump trip tube will be moved lengthwise in the same direction to move the collar 49D¹ from the position shown in dotted lines at least to the position shown in solid lines thereby locking the 50 pump out of action.

All of the structure so far described was 55 in use prior to my invention and is here explained only to facilitate a clear understanding of my invention. The operation of 60 these parts and without my invention being applied thereto, is substantially as follows: When the rod 15D³ is moved into position to operate the justification wedge lever 13D, the latter engages with the end of the galley trip rod rock lever 9D¹ and the galley

trip rod is given a forward stroke due to the engagement of the rock lever with the other wedge lever. When the other rod 15D³ is moved into operative position, the justification wedge lever 14D is operated and the galley 70 trip rod is given a forward stroke. The lengths of the strokes differ and the stroke produced by the justification wedge lever 13D is longer than the stroke produced by the justification wedge lever 14D. The forward movement by the justification wedge lever 14D, that is, the shorter stroke, operates to lock the pump by the engagement of the collar 49D¹ with the pump latch 33H¹. The longer stroke produced by the justification 75 wedge lever 13D not only locks the pump but also operates the trip lever 45F.

One feature of my invention is the means for giving the galley trip rod its longer stroke upon the operation of the justification wedge lever 14D instead of by the justification wedge lever 13D. In order to accomplish this, I provide the rear end of the galley trip rod with a hook X¹. This hook has an eye through which the galley trip rod extends and it is locked rigid in respect to said galley trip rod by suitable adjustable lock nuts X² forming an adjustable stop for the trip rod. The hook extends into engagement along the upper surface of the galley trip rod arm 9D and the upturned or hook end is in the path of the justification wedge lever 14D. Thus, when said justification wedge lever is moved into engagement with the rod lever 9D¹, the movement of the latter about its fulcrum pin is limited by coming into contact with the hook X¹ and the lever is caused to move forwardly bodily with the galley trip rod. 90

A second feature of my invention is the means employed for locking the galley trip rod forwardly at the end of its short stroke and preventing its return until after it has performed its long stroke. This mechanism includes a post X³, which is rigidly secured to the galley trip rod at its forward end and extends outwardly laterally therefrom. This post may move into or out of a recess X⁴ in the frame of the machine, and at the outer end of the post is a pawl X⁵. This pawl is free to swing in a vertical plane and is normally drawn down to a limiting position by a spring X⁶. Rigidly secured to the bed of the machine adjacent the outer end of the pawl, is a stud X⁷, having upwardly-extending side branches X⁸, between which the pawl X⁵ extends. The pawl has a depending lug X⁹ on its under side and two oppositely-disposed projections X¹⁰ extending outwardly upon opposite sides thereof. The stud carries a vertically-movable pin X¹¹, normally pressed upwardly by a coil spring X¹² and into the path of the depending lug X⁹. The two side branches X⁸ have inwardly-directed cam lugs X¹³, as 110 115 120 125 130

shown particularly in Fig. 2, and beneath which the projections X^{10} may travel. The stud X^7 is held in position by a nut X^{14} , while the pin X^{11} is limited in its movement 5 by a combined guide and lock at the lower end of the stud. As shown, the lower end of the stud is provided with a transverse slot X^{15} , and the pin X^{11} has two lock nuts X^{16} , between which is held a guide X^{17} , having two branches disposed within said slot 10 upon opposite sides of the pin. This guide prevents any rotation of the pin, but, at the same time, permits it to reciprocate. The ends of the branches by engaging in the bottom of the slot, limit the upward movement 15 of the pin under the influence of the spring, and thus these guiding branches also serve as stops.

The operation of the mechanism is substantially as follows: The parts are normally in the positions indicated in Fig. 5, that is, the free end of the pawl rests upon the upper end of the pin X^{11} and the two justification wedge levers 13D and 14D are 20 out of engagement with the rock lever 9D¹. Upon the operation of the justification wedge lever 13D, which is the first lever to operate in the normal running of the machine, the parts are moved to the position 25 shown in Figs. 1 and 6, that is, the galley trip rod is given its shorter stroke and this stroke forces the projection X^9 of the pawl X^5 against the pressure of the pin X^{11} and past said pin so that the pawl and pin 30 interlock preventing the galley trip rod returning. At the same time projections X^{10} are brought beneath the cam lugs X^{13} , so that the pawl cannot swing upwardly. It 35 is thus evident that the galley trip rod is positively locked against return movement, and as the galley trip rod cannot return, the pump trip tube 49D cannot return and the pump is locked against operation but the galley trip has not been operated by this 40 short stroke. Upon the operation of the justification wedge lever 14D, the parts are moved to the position indicated in Fig. 7, that is, the galley trip rod is given its longer 45 stroke by reason of the engagement of the rock lever 9D¹ with the hook X^1 , and the projections X^{10} will be carried beyond the farther side of the cam lugs X^{13} . The pin X^{11} raises the pawl to such a position that 50 as the galley trip rod returns the projections X^{10} will ride up over the upper surface of the cam lugs X^{13} and the galley trip rod can freely return to the position indicated in Fig. 1.

By means of my improved mechanism, the 55 keyboard operator when he finds that any portion of a line has been incorrectly recorded on the perforated strip and he does not want this defective line to be cast on the casting machine, can prevent this casting by depressing any of the justification

keys on the lower justification key row on the keyboard. After operating such key he re-records the line as it should be in its proper shape and properly justifies it by the operation of the two justification keys. 70 When the perforated strip is fed to the casting machine, it travels in the reverse direction from the direction of travel during the perforating operation. Thus, when the portion of the paper upon which the incorrectly recorded line is found, reaches the air openings, the opening produced by the key of the lower key row on the keyboard, admits air to operate the justification wedge lever 13D, and this gives the galley trip rod its short 75 stroke. The galley trip rod is locked by my improved mechanism, and the pump is also locked against operation. As the paper continues to pass through the machine the pump will remain locked until an opening 80 appears in the paper which was produced by a key of the upper key row on the keyboard, which will give the galley trip rod its longer stroke and release the same and release the pump trip tube. For instance, in 85 forming the record strip shown in Fig. 8, the openings would be formed in order, beginning at the upper end and going to the lower end. The openings *a* and *b* would be produced in the justifying of the previous 90 line, not shown, and the openings *c* and *d* would be produced in justifying the line 95 extending over the center portion of the strip shown. After justifying this line, the operator begins the next line and in recording it, he may make a mistake by the striking of the wrong key or otherwise, and he would then punch the hole *e*. The striking of the key which punches the hole *e*, would 100 reverse the keyboard and put it in normal 105 position ready to begin the line over again. In feeding the strip to the machine, the lower end of the strip reaches the air openings before the upper end, and as the air flowing through the opening *e* locks the 110 pump, the latter will not be released until the opening *c* is reached.

Having thus described my invention, I claim as new and desire to secure by Letters Patent:

1. A monotype casting machine having a pump lock-out mechanism including a rod, means for moving said rod through two different distances, and means for locking the rod against return movement after moving 115 the shorter distance.

2. A monotype casting machine having a pump lock-out mechanism including a rod, a rock lever connected thereto, two justification wedge levers for engaging with said 120 rock lever for reciprocating the rod, and an attachment for imparting a short movement then a long movement to the rod during the operation of the justification wedge levers.

3. A monotype casting machine having a 130

pump lock-out mechanism including a rod, means for moving the same through a limited distance, means for moving said rod through a greater distance, and means for locking the rod against return movement after movement through the limited distance.

4. A monotype casting machine having a pump lock-out mechanism including a longitudinally-movable rod, means for moving the same longitudinally through a limited distance, means for moving said rod through a greater distance, and means for locking the rod against return movement after the shorter distance, said means automatically releasing upon the movement of the rod through its longer distance.

5. A monotype casting machine having a rod and means for moving it a short and a long distance respectively, a pawl pivoted thereto, a pin for engagement with the pawl to prevent the return movement of the rod after movement through a limited distance, and means for releasing the pawl from the pin upon movement of the rod through a longer distance.

6. A monotype casting machine having a galley trip rod, a rock lever pivotally connected thereto, two justification wedge levers for engagement with opposite ends of said rock lever, and means for limiting the swinging of the rock lever when acted upon by one of said justification wedge levers.

7. A monotype casting machine having a galley trip rod, a justification wedge lever for moving said rod, a limited distance in one direction, means for retaining the galley trip rod against return movement, and a second justification wedge lever for moving said trip rod a greater distance and releasing it from said retaining means.

8. In a monotype casting machine, the combination of a galley trip rod, a justification wedge lever for moving said rod a limited distance, a retainer for preventing return movement, and a second justification wedge lever for moving said rod to a further extent and releasing it from said retainer.

50 9. In a monotype casting machine, a galley trip rod, a rock lever pivotally connected

thereto, a justification wedge lever for engaging with one end of said lever to move the rod a limited distance, a second justification wedge lever for engaging with the opposite end of the lever for moving said rod a farther distance, and means for preventing the return movement of said rod after it has completed its shorter movement and prior to the completion of the greater movement.

10. In a monotype casting machine, a galley trip rod, means for moving said rod a limited distance, means for moving it a greater distance, a pawl pivoted thereto, a pin for engagement with said pawl to prevent the return movement of the rod after the latter has been reciprocated to a limited extent, and means preventing the engagement of the pawl and pin upon the return movement of the rod after the latter has moved to its limiting position.

11. In a monotype casting machine, a galley trip rod, a rock lever pivotally connected thereto, a stop carried by said rod for limiting the swing of the rock lever in one direction and independent means for engaging with opposite ends of the lever to reciprocate the rod different distances.

12. In a monotype casting machine, a galley trip rod, a rock lever pivotally connected thereto, a stop carried by said rod for limiting the swing of the rock lever in one direction, said stop being adjustable in respect to said rod.

13. A monotype casting machine having a galley trip mechanism, a pump lock-out mechanism, a member having a short and a long movement and serving to operate the lock-out mechanism upon the shorter movement and the galley trip mechanism upon the longer movement, and means for locking said member against return movement after completing the shorter movement and prior to completing the longer movement.

In testimony whereof I have signed my name to this specification in the presence of two subscribing witnesses.
